CLAIM

The ornamental design for a gift bag with insert pocket, substantially as shown.

DESCRIPTION

FIG. 1 is a perspective view of a gift bag with insert pocket showing my new design;

FIG. 2 is a front elevational view thereof;

FIG. 3 is a rear elevational view thereof;

FIG. 4 is a side elevational view thereof, the opposite side being a mirror image thereof;

FIG. 5 is a top plan view thereof; and,

FIG. 6 is a bottom plan view thereof.
